CLAIM

The ornamental design for a trencher cup tooth as shown and described.

DESCRIPTION

FIG. 1 is a front view of a first embodiment of the trencher cup tooth, which is a right-side trencher cup tooth showing my new design;

FIG. 2 is a rear view thereof;

FIG. 3 is a right-side view thereof;

FIG. 4 is a left-side view thereof;

FIG. 5 is a top view thereof;

FIG. 6 is a bottom view thereof;

FIG. 7 is an isometric view thereof;

FIG. 8 is a front view of a second embodiment of the trencher cup tooth, which is a left-side trencher cup tooth showing my new design;

FIG. 9 is a rear view thereof;

FIG. 10 is a right-side view thereof;

FIG. 11 is a left-side view thereof;

FIG. 12 is a top view thereof;

FIG. 13 is a bottom view thereof; and,

FIG. 14 is an isometric view thereof.

The broken lines in the drawings illustrate portions of the trencher cup tooth that form no part of the claimed design.
